Primary Examiner — Philip S Hyder*(74) Attorney, Agent, or Firm* — Burr & Forman LLP(57) **CLAIM**

The ornamental design for a hammer, as shown and described.

DESCRIPTION

FIG. 1 is a perspective view of a hammer in accordance with an embodiment of the present invention;

FIG. 2 is a right side view of the hammer of FIG. 1;

FIG. 3 is a left side view of the hammer of FIG. 1;

FIG. 4 is a rear view of the hammer of FIG. 1;

FIG. 5 is a front view of the hammer of FIG. 1;

FIG. 6 is a top view of the hammer of FIG. 1; and,

FIG. 7 is a bottom view of the hammer of FIG. 1.

The broken lines of FIGS. 1-7 illustrate portions of the hammer that form no part of the claimed design.

1 Claim, 7 Drawing Sheets(56)
